UNITED STATES PATENT OFFICE.

THOMAS HENRY NASH, OF ST. PAULS CRAY, ENGLAND.

BEATING AND REFINING ENGINE.

1,351,962.

Specification of Letters Patent. Patented Sept. 7, 1920.

Application filed June 3, 1919. Serial No. 301,420.

To all whom it may concern:

Be it known that I, THOMAS HENRY NASH, a subject of the King of Great Britain and Ireland, and residing at Garland Hill, St. 5 Pauls Cray, in the county of Kent, England, have invented certain new and useful Improvements in Beating and Refining Engines, of which the following is a specification.

10 This invention relates to beating and refining engines for pulp, stuff and the like for use in the manufacture of paper and the like.

15 The object of the invention is to provide means whereby the pulp or stuff may be passed through and returned to the beating rolls any desired number of times while giving a continuous flow at the outlet.

20 Heretofore, with certain types of holanders or beating engines, a roll is placed at one side of a deflecting plate. It has been observed that provided the stuff is entered at a point close to the said plate, its path through the beater is that of a more or 25 less well defined stream, gradually progressing toward the outermost part of the roll.

25 In the present invention advantage is taken of this tendency to form streams, inasmuch as the entry of the stuff to the beating engine is regulated for this passage under and reentry to the roll so that a defined number of passages under the roll is assured over the width of the roll. By multiplying the number of rolls a definite number of 30 beatings can be arranged to take place.

Apart from the added efficiency which such a construction provides, any such system gives advantage in treating different types of pulp according to the required amount of 35 treatment peculiar to each class of stuff treated.

Now, according to the present invention, hereafter more particularly described, the rolls are arranged in multiple succession 40 within a common trough and so arranged that the stuff is fed forward by the said rolls in a gradual upward path, allowing it after passing under the furthermost roll to be returned automatically by gravity in defined streams to the first of the series for 45 re-treatment.

The invention also comprises an arrangement for increasing or decreasing at will the width of the stream of stuff issuing from 50 the feed plate in order to increase or decrease the number of times the stuff is to

pass under the rollers as more fully explained hereinafter.

By the use of the invention a large saving in power and time is effected and the 60 stuff more efficiently beaten by not mixing stuff that has partly or fully been beaten with stuff which has not passed under the rolls.

The invention will now be described with 65 reference to the accompanying drawings in which:—

Figure 1 is a sectional elevation of a beating engine constructed according to the invention and

70 Fig. 2 is a plan of Fig. 1.

In the drawings, 1 indicates two containers of usual form for mixing the stuff or pulp, which is fed by gravity down a pipe 2 opening into an inclined feed plate 75 3 of the beating engine, the containers being so arranged as to give a constant feed. The beater comprises sides 4 and bottom 5 of concrete, the sides carrying adjustable bearings 6 for the spindles 7 of a number of 80 beater rolls 8, four being illustrated but this number may be increased or decreased according to the output which it is desired 85 the engine should have. Each spindle also carries a driving pulley 13.

The bottom 5 of the engine is stepped and the rolls 8 are also disposed in upwardly stepped relationship to one another so that a sufficient head of stuff will be maintained to return the stuff after each passage 90 through the rolls. The stuff passes toward the openings 10^a, 10^b, 10^c of a number of return pipes 11 passing beneath the bottom 5 and delivering the stuff through openings 12^a, 12^b, 12^c on to the feed plate 3. An outlet pipe 14 conveys the beaten stuff to the usual stuff chest of a paper making machine. 95

The feed plate 3 is provided with a number of deflectors 15, one being provided between each opening 12 and one for the pipe 100 2. These deflectors comprise a number of flat plates hinged at 16 and operated by a rod 17 connecting all the deflectors and provided with an operating handle 18. A sluice or gate can be used to obtain the same 105 result.

In the operation of the invention stuff or pulp is delivered to the feed plate 3 by the pipe 2, passes in a stream of the desired width for the reason already explained 110 through all the rolls and is returned by the opening 10^a and pipe 11 to be re-delivered

on to the feed plate through the opening 12^a, this operation being repeated automatically so that with the particular arrangement illustrated the stuff returns five times 5 beneath each roll and finally passes away through the pipe 14. If it is desired to pass the stuff under the rolls a greater number of times, the deflectors 15 can be moved for example to the position indicated in dotted 10 lines in Fig. 2 thereby narrowing the stream of stuff which passes from the feed plate to the rolls. At the same time the inlet valve should be partly closed to give the necessary width of flow of material.

15 As soon as the stuff commences to pass away through the outlet 14, the whole bottom 5 of the engine will be covered by a mass of stuff moving toward the left, the whole consisting of a number of streams 20 each of which has passed through the rolls a predetermined number of times.

In this manner the whole of the stuff is very thoroughly beaten and its quality will be uniform throughout as no part of the 25 stuff receives any more or less treatment than any other part.

The bearings 6 of the rolls 8 may in practice be arranged in vertical adjustment so that any of the rolls may be raised to inoperative position in accordance with the 30 requirements of various materials under treatment.

I claim:—

1. A continuous beating and refining engine for pulp, stuff and the like, for use in 35 the manufacture of paper including a series of beating rolls, means for causing said stuff to pass through said rolls, and means for causing said stuff to be returned and 40 refed through said rolls at a different point along the width of the bed of the engine any predetermined number of times.

2. A continuous beating and refining engine for pulp, stuff and the like for use in 45 the manufacture of paper including a series of beating rolls mounted in upwardly stepped relationship, an upwardly stepped bed, a feed plate, means for returning stuff 50 to the feed plate after each passage through said rolls and means for varying the width of the stream of stuff passing from said feed plate in accordance with the number of times the stuff is to pass through said rolls.

3. A continuous beating and refining engine for pulp, stuff and the like for use in 55 the manufacture of paper, including a series of beating rolls mounted in upwardly stepped relationship, an upwardly stepped bed, a feed plate, means for returning stuff 60 to said feed plate after each passage through said rolls, a plurality of openings in said feed plate and an adjustable deflector adjacent each of said openings for varying the

width of the stream of stuff passing from said feed plate in accordance with the number of times the stuff is to pass through said rolls.

4. A continuous beating and refining engine for pulp, stuff and the like for use in the manufacture of paper, including a series of beating rolls mounted in upwardly stepped relationship, an upwardly stepped bed, a feed plate, a plurality of pipes disposed beneath said bed, means whereby the stuff after each passage through said rolls 75 is caused to return through said pipes, a plurality of openings in said feed plate connected to said pipes and an adjustable deflector adjacent each of said openings for varying the width of the stream of stuff 80 passing from said feed plate in accordance with the number of times the stuff is to pass through said rolls.

5. A continuous beating and refining engine for pulp, stuff and the like for use in 85 the manufacture of paper, including a series of beating rolls mounted in upwardly stepped relationship, an upwardly stepped bed, a feed plate, a plurality of pipes disposed beneath said bed, means whereby the 90 stuff after each passage through said rolls is caused to return through said pipes, a plurality of openings in said feed plate connected to said pipes and means for varying the width of the streams of stuff issuing 95 from said openings in accordance with the number of times the stuff is to pass through said rolls.

6. A continuous beating and refining engine for pulp, stuff and the like for use in 100 the manufacture of paper, including a series of beating rolls, means for supporting said rolls in the sides of said engine, a feed plate, pipes passing beneath said bed to return 105 stuff to openings in said feed plate after each passage through said rolls and means for varying the width of the stream of stuff issuing through said openings in accordance with the number of times the stuff is to pass through said rolls.

7. A continuous beating and refining engine for pulp, stuff and the like for use in 110 the manufacture of paper, including a series of beating rolls, means for causing stuff to pass any predetermined number of times 115 through said rolls and means for varying the width of the stream of stuff in accordance with the number of times the stuff is to pass through said rolls.

In testimony whereof I affix my signature 120 in presence of two witnesses.

THOMAS HENRY NASH.
